UNITED STATES PATENT OFFICE.

EDGAR GUGGENHEIM, OF NEW YORK, N. Y., ASSIGNOR TO TREO COMPANY, INC., A CORPORATION OF NEW YORK.

GIRDLE.

1,278,335.

Specification of Letters Patent. Patented Sept. 10, 1918.

Application filed April 14, 1917. Serial No. 162,110.

To all whom it may concern:

Be it known that I, EDGAR GUGGENHEIM, a citizen of the United States, residing at the city of New York, in the borough of Manhattan and State of New York, have invented certain new and useful Improvements in Girdles, of which the following is a full, clear, and exact description.

This invention relates to girdles or corsets and its primary object is to provide an elastic girdle adapted to be worn, particularly by stout persons; it is also an important object of my invention to provide a combined elastic girdle and abdominal support. These objects are attained by the construction which will be hereinafter described in detail in connection with the accompanying drawing, in which—

Figure 1 is a plan of the improved girdle or corset when opened out flat;

Fig. 2 is a perspective elevation of the front of the corset, with its extremities brought together and fastened in the manner in which it is worn.

The body of the girdle is mainly composed of a wide band of elastic textile fabric 1, its elasticity being in the direction of its length only. This band is without gores or darts, or in other words, is entirely unshaped to the figure, except that its lower edge may be longer than its upper edge in order to provide for the larger girth of the hips than the waist. The band is in all its essential respects similar to the band described in U. S. Patent Number 1,104,664, granted to me July 21, 1914, and all of the advantages of that structure are embodied in the present device. At the waist line this band is provided, as in the patented girdle, with a zone 2 of elastic but less yielding nature than the body of the band. The band along the line of this zone 2 is for the best results approximately equal in length to the natural waist size of the person who wears the garment, and the band being more rigid along this line is held from slipping downward or upward either by exertion or the drag of the hose supporters which are commonly attached to the lower edge of the garment.

The band 1 being uniformly elastic throughout is, when worn by stout persons, subjected to widely different strains along

different zones, and the elastic therefore not only wears out more quickly but its reducing effect is less. Accordingly, my invention consists in adding to the lower portion of the band a reinforcing elastic web 3, which is sewed along its vertical edges 4—4 to the face of the band 1, while its horizontal edges 5—5 are free. Other vertical lines of stitching 6—6 may also extend across the face of this reinforcing band and secure it to the main band 1, if desired. In the same zone with this reinforcing elastic band 3, I attach as a continuation thereof on each side, inelastic sections 7—7 of coutil, or other rigid fabric, which are likewise secured along their vertical edges 8—8 by means of stitching, while being left free along their horizontal edges 9—9. Each of these rigid sections is in two parts connected together by lacings 10, so that the parts can be drawn together to any extent desired in order to determine the limit of the stretching of the elastic band 1 in the region immediately behind the said rigid sections 7—7.

The front of the garment is provided with the usual busks which carry the fastening devices 11, ordinarily used on corsets, or any other suitable fastening means, and the extremities of the band have pads 12—12, respectively, made of inelastic material in which are incorporated a number of bones 13, to produce a stiff supporting shield.

When this garment is worn, it will be seen that the lower half of it, which covers the hips, will resist the excessive strains at that location better than if the garment was single-ply throughout, and that the reducing effect of this portion of the garment will be more pronounced than if the main band were not reinforced by the portions 3. The rigid sections 7—7 can be adjusted by means of their lacings to limit the amount of stretch of the band 1 in the region immediately under the sections so that the lower front portion of the garment at which location these rigid sections occur, will serve as an adjustable abdominal supporter, making it unnecessary to use a supporter of this kind in addition to an ordinary corset or girdle. By leaving the lacings very loose the elastic material behind the sections 7 will have full play. It is obvious that adjustable rigid sections similar to the sections 7 can be

placed on the band 1 at any points where it is desired to limit the elasticity of the band.

I claim:

- 5 1. The combination with a girdle, elastic in the direction of its length, of inelastic sections adjustable lengthwise of the girdle and attached to the face of the girdle.
2. A girdle comprising a band, elastic in

the direction of its length and provided at 10 the lower front portion with inelastic sections adjustable lengthwise of the girdle and attached to the face of the band, substantially as described.

In witness whereof I subscribe my signature.

EDGAR GUGGENHEIM.
